UNITED STATES PATENT OFFICE.

RICHARD A. MURRAY AND LOGAN H. HOOPER, OF MUSKOGEE, OKLAHOMA.

CLASSIFICATION BOX.

Application filed August 17, 1922. Serial No. 582,454.

To all whom it may concern:

Be it known that we, RICHARD A. MURRAY and LOGAN H. HOOPER, citizens of the United States, residing at Muskogee, in the county 5 of Muskogee and State of Oklahoma, have invented certain new and useful Improvements in Classification Boxes, of which the following is a specification.

This invention relates to new and useful 10 improvements in signalling devices and more particularly to the type known as classification boxes, which are designed to be located on the front of a steam locomotive for signalling passing trains and stations and 15 towers situated along the tracks.

An important object of the invention resides in the provision of a device of this character which is permanently attached to the forward end of a locomotive so as to 20 obviate the necessity of the engineer or fireman making hazardous climbs to the forward end of the locomotive in order to give the required signals to passing trains, and wayside stations.

25 The device is also constructed of metal or any other suitable indestructible material so as to obviate the necessity of renewing signalling devices from time to time such as the fabric flags which soon fall into disuse 30 due to their inability to withstand general weather conditions and constant usage.

Another object of the invention resides in the provision of a signalling device including an illuminated casing which houses a 35 "flag" of a particular color which is so arranged with respect to the casing that when the flag of a particular color is projected from the casing to a displaying position, a light of the same color as the flag will be 40 visible from the front and one end of the casing.

A further object of the invention resides 45 in the provision of a signalling device of this character which includes a plurality of different colored "flags" which co-operate with means for simultaneously displaying a light of the same color as the flag which is arranged in displaying position.

A further object of the invention resides 50 in the provision of a simple and inexpensive means for displaying the flags and also means for automatically concealing the flags in a protected position when their display is no longer required.

55 Another object of the invention resides in the provision of a plurality of different

colored movable flags which are normally concealed from view and each of which is provided with a pair of transparent portions of a color corresponding to that of the flag 60 so that when both flags are disposed within the casing provided for housing the same, a safety light will be displayed from the front of the casing.

Other objects and advantages of the invention will become apparent during the course of the following description.

In the accompanying drawings forming a part of the description and wherein like numerals are employed to designate like parts 70 throughout the several views:—

Figure 1 is a fragmentary top plan of a steam locomotive with the invention applied thereto,

Figure 2 is a vertical transverse section 75 through one of the signal devices,

Figure 3 is a perspective view of one of the "flags" associated with each signal device,

Figure 4 is a longitudinal vertical section 80 through the signal device showing one of the "flags" arranged in a semi-displaying position, and

Figure 5 is a perspective view of the outer end of the signal device with one of the 85 "flags" arranged in displaying position.

Referring now more particularly to the drawings, and wherein for the purpose of illustration is shown the embodiment of the invention which is at present preferred, the 90 numeral 6 designates the forward end of a steam locomotive having the usual smoke stack 7 projecting upwardly therefrom. A signalling device or classification box 8, which in the present instance consists of a 95 rectangular casing, is mounted at the forward end of the locomotive on each side thereof to project laterally beyond the boiler as clearly shown in Fig. 1. Any suitable means may be used in supporting these boxes 100 on the locomotive. As both boxes are of identically the same construction, only one of them will be described.

The front of the casing 8 is designated by the numeral 9 and is adapted to be arranged 105 facing forwardly of the locomotive and is provided with an opening 10 or bull's-eye in the outer upper corner as clearly seen in Fig. 5. This opening is equipped with a transparent lens the color of ordinary 110 glass. One end 12 of the casing which is the end arranged furtherest from the loco-

2
motive, is provided with a pair of spaced vertical slots 13 and 14 for a purpose which will be presently described. This end of the casing, in its upper rear corner is provided 5 with an opening 15 which is covered by a transparent element or lens 16. The back of the casing consists of a hinged closure 17 which is imperforate with the exception of an opening 18 in its upper inner corner, 10 which opening is covered by a transparent element or lens 19 so that a source of light 20 which may be connected, or any other suitable kind may be seen by the engineer so that at all times he will be informed 15 whether or not the casing 8 is properly illuminated. This source of light 20 in the present instance consists of an incandescent light bulb which is situated at the inner end of the casing adjacent the top thereof. Any 20 suitable kind of fastening means may be provided for retaining the hinged closure 17 in a closed position so as to render the interior of the box or casing 8 weatherproof.

An axle or shaft 21 is extended trans- 25 versely through the outer lower corner of the casing 8 and has its opposite ends journaled in the front and rear of the casing as best seen in Fig. 2. This axle is prevented from displacement by means of a 30 collar 22 keyed to each end of the axle so as to abut the adjacent portions of the casing as shown. A pair of so called "flags" 23 and 24 are loosely mounted in spaced relation on the axle 21. However, these 35 flags are not flags as the term is ordinarily understood to mean fabric flags, but they consist of elements made of rigid material such as hard wood or metal. The flags are painted different colors and in the 40 present instance the flag 23 is wholly white, while flag 24 is entirely green. Each of the flags has secured to a side thereof, a small pinion 25 each of which has an opening therethrough arranged concentric with 45 the opening in its respective flag and through which the axle 21 passes. Each of the flags consists of an L-shaped rigid member having an opening 26 at the juncture of its two arms as shown in Fig. 3 50 for the passage of the axle 21. A coiled spring 27 is provided for each flag and has one end secured to its respective flag adjacent the juncture of the two arms of 55 the flag, while the opposite end of the spring is fastened to the bottom of the casing 8 at a substantial distance away from the axle 21 so as to normally exert a pull inward of the outer end of the casing so as 60 to retain the flags normally disposed there- 65 in, so that one arm 23^a of each flag is ar- ranged horizontally in the bottom of the casing, while the other arm 23^b of the flags are disposed vertically. The arm 23^b of each flag is provided with a transparent element 28 which is of rectangular config-

uration as shown in the present instance and is the same color as the flag and fits in a cut out portion of corresponding configuration extending from the free end of the arm to a point adjacent its juncture with the 70 co-acting arm. The edges of this cut out portion are grooved to retain the edges of the transparent element as shown to advantage in Figs. 3 and 5. The white transparent element 28 of flag 23 is provided with a circular portion 29 which is adapted to align with the bull's-eye 10 in the casing when the arm 23^a is disposed wholly therein. The arm 23^a of each flag is provided with an opening 30 for the reception of a transparent 75 element 31 which is the same color as the arm with which it is associated. As the two flags are arranged in the same horizontal plane when disposed within the casing 8, it will be seen that the transparent 80 elements 28 of the two flags will be in alignment and light from the electric bulb 20 within the casing will show through the aligning transparent plates 28 of the two flags, and since one of the transparent portions is green, a green light will be shown through the bull's-eye 10 in the front of the casing. 85

The green flag 24 has the upper edge of its horizontal arm 23^a provided with a right 90 angularly extending lens holding portion 32 which adjacent the free end of the arm 23^a is provided with an opening covered by a green lens or transparent element 33 which transparent element is adapted to be 95 brought into alignment with the transparent element 16 in the end 12 of the casing, when the green flag is moved to a displaying position as shown in Fig. 5 so that a green light will be visible through the opening 100 15. When the green flag is in this position, it will be obvious that a transparent element 31 carried by the green flag will be 105 arranged in alignment with the plain transparent portion 29 of the white flag and also the bull's-eye 10 so that a green light will be visible through the bull's-eye and through the opening 15 in the end of the casing, while the arm 23^b of the green flag will be projected through the slot 14 110 to extend outwardly from the end 12 of the box or casing. 115

When the green flag is disposed within the casing and the arm 23^b of the white flag is projected from the casing, the transparent element 31 of the white flag will be aligned with the bull's-eye 10 and a white light will be visible therethrough. The lens carrying portion 32 of the green flag being disposed horizontally below the opening 15 in the end of the casing, white light will also be projected through the transparent element 16. It will therefore be obvious that two lights, one in the front of the casing and one in the side thereof will be visible at 120 125 130

all times, and the color of these lights will correspond with the color of the flag projected from the casing. When both flags are disposed within the casing, transparent element 28 of the green flag 24 will be aligned with the bull's-eye 10 and the transparent element 29 of the white flag so that a green light will be visible through the bull's-eye in the front of the casing, while 10 a white light will be visible through the end 12 of the casing.

For projecting the flags from the casing to a displaying position, a rack bar 34 is provided for each flag and is arranged 15 alongside of the flag so that the teeth thereof mesh with those of its respective pinion 25. This rack bar is held in engagement with its respective pinion by means of a bracket 35 fastened to the bottom of the 20 casing and extending upwardly so that its upper angular end overlaps the top of the rack bar as shown to advantage in Fig. 2. Spacing sleeves 36 are provided on the axle 21 to hold one of the brackets 35 spaced 25 from the green flag 24 and its coil spring 27, while another one of the sleeves is provided to hold the bracket 35 in upright position and spaced from the rear closure 17 of the casing as shown.

30 In the present instance, each rack bar 34 constitutes the stem of a piston hood which is arranged within a cylinder 37 carried by the forward end of an air pipe 38 so that air pressure is employed to operate the signals. The rack bars of the classification boxes extend through the inner ends of their respective boxes, and each constitutes the stem of a piston as hereinbefore explained. The pipes 38 lead to the cab of the locomotive and air pressure thereto is controlled 40 by the engineer so that by permitting air to enter the cylinders 37, the flags are caused to be projected and when air pressure in the pipes is released the coil springs 27 return the flags back to position within the casing. It will be understood that the rack bars of the white flags are controlled independently from those of the green flags, and the white flags at the sides of the locomotive may be simultaneously operated, or one 45 at a time whichever is desired.

The foregoing description and accompanying drawings have reference to what might be considered to be the approved or preferred form of our invention. We desire it to be understood that we may make such changes in the construction, combination and arrangement of parts, materials, dimensions, et cetera, as may prove expedient and fall 50 within the scope of the appended claims.

Having thus fully described the invention what we claim is:—

60 1. A signaling device comprising an illuminated casing having an opening therein through which light from the casing is pro-

jected, a movable flag associated with the casing and having a pair of transparent portions, one of said transparent portions being adapted to align with the opening in the casing when the flag is within the casing 70 while the other transparent portion is adapted to align with the opening when the flag is extended out of the casing to display a light from the opening corresponding to the color of the flag. 75

2. A signalling device comprising an illuminated casing having an opening therein a movable signalling arm movable into and out of the casing, said signalling arm being of a color indicating a certain condition, and transparent means co-operating with the opening in the casing for causing a light corresponding in color to that of the signalling arm to be visible through the opening in the casing when the signalling arm is arranged 80 in a displaying position. 85

3. A signalling device comprising an illuminated casing having an opening therein, a signal arm movably associated with the casing, and having transparent means to cause a light of a certain color to be projected through the opening in the casing when the arm is arranged in a displaying position and to cause a different light to be visible through the opening when the signalling arm is arranged in a non-indicating position. 90 95

4. A signalling device comprising an illuminated casing having an opening therein, a pair of signal arms movably associated side by side within the casing and having transparent portions adapted for alignment with the opening in the casing and with each other whereby different colored lights can be exhibited through said opening depending upon the relative position of the signalling arms. 100 105

5. A signalling device comprising an illuminated casing having an opening therein, a pair of L-shaped signalling arms movably associated therewith, the arms of each L-shaped signalling arm being provided with transparent portions adapted to align with the opening in the casing whereby different lights are exhibited through the opening in the casing depending upon the relative positions of the signalling arms. 110 115

6. A signalling device comprising an illuminated casing having an opening therein through which light from the casing is projected, a movable flag associated with the casing and having a colored transparent portion associated therewith and adapted to align with the opening in the casing when the flag is arranged in an indicating position. 120 125

7. A signalling device comprising an illuminated casing having a slot and an opening in a wall thereof, a flag movably associated with the casing and adapted to be nor-

mally arranged inside thereof and being projectable through the said slot, and said flag having an angularly disposed portion equipped with a colored transparent element 5 adapted to be brought in alignment with the opening in the casing when the flag is projected through said slot.

8. A signalling device comprising a casing having a slot therein, a signalling arm 10 pivotally mounted within the casing and adapted to be projected through said slot, a pinion carried by said arm, and a rack bar movable through the casing and engageable with said pinion for moving said arm to an 15 indicating position.

9. A signalling device comprising an illuminated casing having an opening associ-

ated with a wall thereof, and a slot in the wall arranged at right angles to the wall having the opening, an L-shaped signalling arm 20 pivotally mounted within the casing and having a pair of transparent colored portions, one of which is adapted to align with the opening in one position of the arm while the other is adapted to align with the opening 25 in the other position of the arm.

In testimony whereof we affix our signatures in presence of two witnesses.
